UNITED STATES PATENT OFFICE.

MORRIE BRAND, OF SAN FRANCISCO, CALIFORNIA, ASSIGNOR OF ONE-HALF TO JOSEPH HUGHES, OF SAN FRANCISCO, CALIFORNIA.

DOOR CLOSER-HINGE.

1,214,748.

Specification of Letters Patent.

Patented Feb. 6, 1917.

Application filed June 1, 1916. Serial No. 101,086.

To all whom it may concern:

Be it known that I, MORRIE BRAND, a citizen of the United States, residing at San Francisco, in the county of San Francisco and State of California, have invented certain new and useful Improvements in Door Closer-Hinges, of which the following is a specification.

This invention relates to certain new and useful improvements in door closer hinges for double acting swing doors and the like and it has for its objects among others to provide a simple, cheap, yet efficient, durable and reliable hinge, composed of few parts, those readily assembled, not liable to get out of order and which dispenses with all heavy cumbersome springs, boxings and plates such as heretofore used and which will work freely and lightly and without any undue accelerated movement.

My improved hinge allows the setting of doors to be almost air-tight, and provision is made for adjustment to keep the door close to the head jamb.

I provide a beveled wheel which practically avoids all friction and gives a quick and easy action.

By the employment of a hinge, such as hereinafter disclosed, one is enabled to hang a double action swing door with ease and rapidity and with little labor.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a vertical section showing my improved hinge applied to a door. Fig. 2 is a cross section on the line 2—2 of Fig. 1, looking in the direction of the arrows. Fig. 3 is a bottom perspective view of the wheel box plate with the barrel broken away. Fig. 4 is a perspective view of the adjusting plate. Fig. 5 is a perspective view of the floor plate.

Like numerals of reference indicate like parts throughout the several views.

The invention is capable of embodiment in a variety of forms, that herein shown being what I consider, at the present time, most desirable.

Referring to the drawings, 1 designates a door and 2 its frame.

3 is a floor and 4 a plate having at each corner a hole 5 for the reception of screws 6 by which it is secured to the floor with one edge close up to the jamb, as seen in Fig. 1. This plate is provided substantially centrally with an opening 7 and another opening 8 for the reception of screws soon to be described. It is further provided between the hole 7 and the end of the plate that goes against the jamb with an elongated opening 9 adapted to register with a hole 10 made in the floor, as seen in Fig. 1.

11 is an adjusting plate provided with transversely elongated openings 12 and 13, as seen clearly in Fig. 4, and adjacent one end with a hole 14 and with a horizontally disposed substantially U-shaped member 15, the upper face of which is beveled, as at 16, from the longitudinal median line in opposite directions lengthwise of the side portions of said member.

17 is a plate secured by screws or the like 19 to the under face of the top of the door frame.

20 is a plate secured to the top edge of the door by screws or the like 22, the plates 17 and 20 being set in flush, the plate 20 having an upwardly extended pin 23 engaging a hole in the plate 17 and a corresponding hole 25 in the top of the frame.

In practice, a washer 26 is usually employed surrounding the pin 23 and interposed between the plates 17 and 20 so as to keep the door from rubbing the upper portion of the frame or head jamb.

27 is a plate having holes 28 for the reception of screws 29 for securing it to the bottom edge of the door, said plate being set in flush, as seen in Fig. 1. Integral with or fixed to this plate 27 is a barrel 30 and a pin 31 projects downwardly from said plate and adapted to pass through the opening 14 in the adjusting plate 11 and through the elongated opening 9 in the plate 4 and into the hole 10 in the floor, as seen in Fig. 1. This barrel is adapted to be inserted in a hole 32 bored in the door from the under side, and movable through an opening 33 in the bottom of said barrel is a yoke 34 mounted for reciprocation therein and having a stem or rod 35 which passes through an opening 36 in the head 37 at the inner end of the barrel,

the end of said stem or rod being screw-threaded, as at 38, and receiving a nut 39 bearing against the end 37 of the barrel. Around this stem or rod is a spring 40 having a bearing at one end against the inner face of the head 37 and at its other end against the yoke 34, all as seen clearly in Fig. 1. Mounted in the yoke 34 to revolve freely is a bevel wheel 41 which is adapted 10 to travel on the cam or inclined faces 16 of the member 15 on the plate 11.

The bevel wheel riding on the inclined faces 16 of the member 15 reduces the friction to a minimum and insures a quick and 15 easy action.

By making the stem 35 screw-threaded and providing the nut 39, I can readily raise or lower the stem so as to tighten or loosen the spring and thus keep the door almost 20 perfectly tight to the head jamb.

The elongated slots 12 and 13 in the adjusting plate 11 permit of adjustment of the plate in either direction, as may be desired, to bring the pins 23 and 31 in direct 25 vertical alinement, as existing circumstances may require.

Modifications in details may be resorted to without departing from the spirit of the invention or sacrificing any of its advantages.

What is claimed as new is:—

1. A door closer hinge embodying a plate for attachment to the floor, an adjusting plate for coöperation therewith having oppositely disposed cam faces, a plate for attachment to a door having a depending 35

member engaged in coincident openings in said plates, a tubular member and a spring-actuated beveled wheel movable within said tubular member and engageable with said 40 cam surfaces.

2. A door closer hinge comprising a plate for attachment to the floor and having an elongated slot, an adjusting plate having transversely elongated slots and a plate for attachment to a door having a pin engageable in an opening in said adjusting plate and in the elongated slot of the floor plate, said adjusting plate having a member with oppositely disposed cam surfaces and a 50 spring-actuated wheel engageable with said cam surfaces.

3. In a door closer hinge, a plate attachable to the bottom edge of a door and having a depending pin and an upwardly extended barrel, a stem guided in said barrel, a wheel revolvably carried by said stem, a spring around said stem and means for adjusting the tension of the spring, combined with a plate attachable to the floor and a plate for coöperation therewith having an elongated slot and having cam surfaces for engagement by said wheel, the said depending pin engageable in coincident openings in the two last-named plates.

In testimony whereof I affix my signature in the presence of two witnesses.

MORRIE BRAND.
